Geo. H. Hoagland

United States Patent Office.

GEORGE H. HOAGLAND, OF PORT JERVIS, NEW YORK.

Letters Patent No. 69,485, dated October 1, 1867.

IMPROVED CHAIR.

The Schedule referred to in these Letters Patent and making part of the same.

TO ALL WHOM IT MAY CONCERN:

Be it known that I, GEORGE H. HOAGLAND, of Port Jervis, in the county of Orange, and State of New York, have invented a new and useful Improvement on Chairs, of which the following is a full, clear, and exact description, reference being had to the accompanying drawing, forming part of this specification, and in which—

Figure 1 represents a side view of a chair constructed according to my improvement.

Figure 2, a back view of the same, and

Figure 3 a plan thereof.

Similar letters of reference indicate corresponding parts.

The working loose and breakage of chairs, by reason of the multiplicity of parts in which they are usually made, and fastening of the same by glue, is a constant source of annoyance and expense. To obviate this is one of the objects of my invention, the nature of which consists in uniting the seat-frame to the sides; also the back to the latter by metallic fastenings, of a dove-tail shape or character, permanently fitted to said parts of the chair, and locking or fitting, in a readily attachable and detachable manner, the one within the other, to facilitate the putting of the chair together, firmly holding the same when the several parts are united, and admitting of the chair being packed in a small space or compass for transportation.

Referring to the accompanying drawing, A represents the sides of the chair, each of said sides, consisting of the legs *a a* and top connecting-bar *b*, being formed of a single strip of wood, bent, say by steaming and subjecting it to the action of a mould or former, into a symmetrical shape, the two sides corresponding to each other. This construction of the legs and upper connecting-bar makes a light but strong side frame. The back *B* is or may be similarly formed in one piece also, for the most part, that is, three of its sides or bars, the seat-frame *C*, thus avoiding glued joints and a multiplicity of parts, to the better preservation of the chair from breaking or its parts working loose. To give increased stability to the chair, and yet further avoid the use of glue for securing the parts together, and to facilitate putting together the chair and ready detachment of its sides, seat, and back, I provide these parts with mortise and tenon metallic fastenings *c d*, of a dove-tail shape, let into the wood and firmly secured thereto, whereby the seat-frame *C* and back *B* may be made to interlock in an easy but most stable manner with the side frames *A*, and such parts of the chair be made to constitute a perfect and strong entirety, capable of ready detachment and packing into a flat or small compass for transportation. These metallic fastenings I prefer to make of malleable cast iron, as being cheap, strong, and admitting of being painted over in common with the wood-work of the chair. Any suitable covering or filling in to the back and seat-frame may be adopted. Where the chair is not of an arm character, then the seat-frame may interlock by its dove-tail fastenings with the top bars of the side frames, but where the construction is that of an arm-chair, as represented by red lines in fig. 1, then the seat-frame, as well as the back, may similarly interlock with the legs or uprights of the side frames. The back *B* may also be connected to the side frames *A* by a cross-bar, *s*, arranged as a swivel or pivot to the back when the seat-frame is withdrawn. To further brace or strengthen the chair, and retain the advantages already specified as regards transportation, and to dispense with glued joints, I make the rungs *E* of the chair, as represented in fig. 1, of any suitable material, and either solid or tubular, but with right and left-hand screw-threads, *e*, at their opposite ends, and made to fit or screw into holes formed in the parts they serve to connect, and whereby, on turning the rungs in a suitable direction, first springing said parts to facilitate entry, the chair is securely braced without liability of the rungs to get loose, and by turning the rungs in an opposite direction and springing the parts the same may be readily detached. A chair thus fitted and constructed may not only be got up cheap, but is strong, durable, easy of transportation, and requires only ordinary instead of skilled labor to put together.

What I here claim, and desire to secure by Letters Patent, is—

The seat-frame and back, or either, secured to the side frames of the chair by means of metallic fastenings *c d*, forming mortise and tenon locks, of dove-tail shape, substantially as specified.

GEO. H. HOAGLAND.
